BUILDING BLOCK AND STRUCTURE
FORMED THEREFROM

Christian F. Sauereisen, Aspinwall, Pa.

Application February 26, 1937, Serial No. 127,855

8 Claims. (Cl. 72—37)

My present invention relates to building blocks or bricks and to floors, walls and other built-up structures made therefrom.

Bricks and built-up structures composed of bricks are usually laid with a plastic mortar or the like for holding the blocks or bricks together. In the case of ordinary rectangular building brick, a row or course of such brick is laid one brick at a time in the plastic mortar which thereafter hardens. For some types of use, as in industry, in the making of plant floors, tanks, walls and analogous structures, such a construction is not satisfactory. In cases where the structure comes in contact with corrosive materials such as acids or corrosive vapors the mortar is attacked and rapidly deteriorates. In other cases it is necessary or desirable to have a surface, i. e., a vertical wall or tank surface, which has no exposed or visible joints and hence wherein corrosive attack is prevented or greatly retarded. With the common form of building brick such is not possible and a number of modified bricks have been proposed in the past to take care of such instances. These prior proposals, however, have for the most part been objectionable in that the special brick shapes required are too difficult to form, requiring special divided molds, etc., and at the same time the expense is unduly increased. Even in those cases where the brick itself is of a relatively satisfactory type, difficulty is encountered in laying the brick, necessitating the use of spacers or pre-cast joining strips. For example, in the construction of acid containers such as tanks for pickling iron and steel it has been found that the best results can be secured by laying brick in molten sulphur or in some other molten composition specially prepared for such service. The use of ordinary rectangular bricks with molten binder is difficult and troublesome, necessitating the pre-casting of sulphur or other strips to form spacers which must be placed between successive courses. Paper strips must then be pasted along every course to seal off the joints.

It is accordingly one of the objects of my present invention to produce a novel brick from which built-up structures can be conveniently made with poured joints.

Another object of my invention resides in the production of brick from which tanks or walls can be made free from visible joints and hence which present a 100 per cent ceramic surface.

A further object resides in a brick of such nature that an entire course is first laid and then liquid or melted binder poured into pre-formed

recesses in the brick, thus obviating the necessity of laying each brick separately in a plastic mortar.

More specifically, my invention resides in the production of a parallelepipedal brick which is especially configured on three surfaces thereof so that when laid connecting recesses or passageways are formed which, when filled with liquid binding material poured therein, causes the brick to be secured in place and to each other in proper position; my invention also contemplates the speeding up of the laying of brick and the forming of built-up structures therefrom.

In the accompanying drawing wherein like numerals designate corresponding parts:

Figure 1 is a perspective view of a brick embodying my present invention and showing a fragment of an adjoining brick;

Fig. 2 is a side elevational view of the brick of Fig. 1;

Fig. 3 is a bottom view of the brick of Fig. 1;

Fig. 4 is a transverse sectional view taken on the line IV—IV of Fig. 1;

Fig. 5 is an elevational view of the brick of one end of Fig. 1;

Fig. 6 is a plan view of a floor formed from the brick of Fig. 1 and a sectional view through a vertical wall extending at right angles to said floor;

Fig. 7 is a sectional view on line VII—VII of Fig. 6;

Fig. 8 is a view showing a section of the floor and an elevation of the wall taken on line VIII—VIII of Fig. 7; and

Fig. 9 is a view similar to Fig. 7 of a modified form of the invention.

Referring first to the brick itself, as illustrated in Figs. 1 to 5, inclusive, the numeral 10 indicates the upper surface thereof. It will be noted that this upper surface is planar. Likewise, the side 11 of the brick is planar, as will be apparent from Figs. 4 and 5 in particular. One end 12 is also planar.

The remaining three surfaces of the brick, namely, the other end 13, the other side 14 and the bottom 15 are specially configured as will be apparent from Figs. 5, 2 and 3, respectively. Referring first to Fig. 5 which illustrates the end of the brick, it will be apparent that this end is characterized by a semi-circular recess or flute 16 substantially centrally disposed. This flute extends from the upper surface 10 of the brick to a point 17 short of the bottom of the brick and from such point to the bottom there is provided a somewhat semi-circular beveled portion 18 which together with flute 16 forms 55

an inverted funnel-shaped recess and it will be noted that the lower edge 19 of this portion 18 is above the extreme lowermost point of the brick. From the flute the end wall of the brick is provided with the two portions 20 which are non-vertical being inclined from top to bottom, that is, the upper edge of these portions is inwardly disposed relative to the bottom edge thereof and also these walls are inclined from the flute toward the corners of the brick. Thus these portions 20 have a double or compound slope or inclination both vertically and horizontally. These portions 20 do not, however, extend all the way to the edges of the brick, thus forming marginal portions 21 which consequently are of somewhat wedge shape having their thinnest portion at the bottom and their thickest portion at the top. 20 and 21 are joined by triangular bevel walls 22. It will be further noted that one edge of the flute (the left edge in Fig. 5) extends the entire height of the brick whereas the other has a flaring lower end designated by the numeral 23.

The non-planar side 14 of the brick (Fig. 2) is generally of the same nature as the non-planar end 13 just described, the major difference being in the proportions. The non-planar side has a flute 23 which is off-center (but which may be centered if desired) and which has a semi-circular beveled portion 24 which together with flute 23 forms an inverted funnel-like recess and it will be noted that the lower edge 25 of this portion 24 is also above the lowermost point of the brick. From the flute the brick side walls 26 have the compound inclination described in connection with walls 20 of Fig. 5 and hence wall portions 26 in Fig. 2 have their upper edges inwardly disposed with relation to their lower edges and also slope from the flute toward the corners, the innermost point being at the flute. In this manner marginal edge portions 27 are formed which are of wedge shape, this is, their lower portions are the thinnest and merge with the side wall of the brick and their upper portions are the thickest. Wall 26 is connected to portions 27 by triangular bevel walls 28. It will be noted, however, that both the marginal portions 27 of Fig. 5 and the marginal portions 21 of Fig. 2 are actually vertical and that the fact that they are wedge shaped arises from the sloping of the in-between portions and not from any alteration in the marginal portions themselves.

It will be noted that the bottom 15 of the brick (Fig. 3) is almost entirely cut away or recessed, leaving only a longitudinal marginal strip 29 along one side of the brick and two segmental portions 30 on the opposite corners of the brick. These three portions rest upon the top of a subjacent course of bricks and form between the two courses recesses which are adapted to receive a liquid binding or joining material. Attention is also called to the fact that the inverted funnel-like recesses provide communication with the recess in the bottom of the brick. This is taken advantage of in laying and uniting the bricks as will be pointed out hereinafter.

From a consideration of the above description and Figs. 1 to 5, inclusive, it will be understood that I have provided a parallelepipedal brick having three planar surfaces and three non-planar surfaces and that the non-planar surfaces are so configured and related to one another that when a plurality of bricks are laid either upon a suitable foundation or upon a subjacent course the bricks can be secured to one another and to the foundation or subjacent course

by pouring a liquid binding or joining material into the inverted funnel-like recesses. Such liquid material flows into the recess in the bottom of the brick and spreads along into the bottom recesses of contiguous bricks but the flow of such liquid material is laterally limited on one side by the longitudinal bottom marginal portion 29 and on the other side by the two segmental portions 30 thus preventing any undesirable spreading, flowing or wasting of the liquid material. This liquid material is poured hot or in melted condition and when it cools or hardens forms an effective joint securing the bricks to each other and to the foundation or subjacent course. Thus in utilizing the present brick in producing horizontal surfaces, such as floors, an entire course of brick may be laid and then the joints poured. Pouring is carried out via each funnel-like recess. Such a floor is illustrated in Fig. 6 especially and of course in such a floor the joints on the top course are exposed or visible unless covered by a layer of tile or other material which may or may not be resorted to, depending upon circumstances. The longitudinal joints are designated by numeral 31 and the transverse joints 32 by numeral 33. I am thus able to produce an exceptionally strong and even brick floor in a simplified manner and in a much shorter period of time as compared to ordinary brick having six planar surfaces and wherein each brick must be set individually in a plastic mortar and each course leveled off. In a floor made of my new brick a level floor is insured without any special precautions being taken provided the foundation is itself level. The exposed joint material is also minimized being only a fraction of that where regular rectangular bricks and plastic mortar are used.

Such liquid binding or joining material may be of any known or desired composition and I do not in this application claim per se novelty or invention in such composition, since a number of these are known in the art. The composition may, however, either be one which is normally liquid and which hardens or sets when in place or after a given period of time or it may be a material which is hard or solid at normal temperatures and which is liquid at raised temperatures. Sulphur is one material that may be successfully used. In such case the material is poured hot and hardens upon cooling and in connection with the use of a liquid joining material it will be noted that there can be no waste of the same because the recesses are filled substantially full and hence the material is utilized more economically than plastic mortar or analogous materials which are wasteful in that an excess must always be used and the excess removed. My present invention also provides neater joints having no projecting portions and thus has additional advantages over the use of plastic mortars.

Ceramic surfaces may be produced from brick made in accordance with the present invention which have no exposed or visible joints and this is particularly useful in connection with walls or tanks as above outlined where corrosive conditions or agents exist which would attack ordinary mortar joints or any joints of an exposed nature or for ornamental purposes.

Such surfaces have also been indicated in Figs. 6, 7 and 8 and it will be observed from Fig. 8 in particular that there are no visible or exposed joints or joining material in the vertical wall there shown. In building such surfaces it will be appreciated that the bricks, as shown in Figs. 7

1 to 5, inclusive, may be so assembled that their planar sides 11 are the ones which are exposed to view and form the visible surface. Such will be understood by referring to the bricks marked 5 10a in Figs. 6 to 8 and, as shown, these bricks may abut against a concrete or other wall or surface 33 depending upon the particular use. In Figs. 6 to 8, inclusive, the vertical wall with the invisible joints is made from brick of the same 10 size as the flooring brick but in Fig. 9 a narrower slightly modified brick 10a' has been used having different proportions but otherwise being substantially the same as is indicated by the use of the same numerals thereon with a prime (') 15 designation.

Vertical walls or tanks may thus be formed which are permanent and proofed against deterioration, particularly where corrosive atmospheres or agents are present, but the use of the 20 brick is not limited to such because I have discovered that subway tubes or vehicular tunnels can be advantageously so produced and in such cases where it is desired to make the built-up structure impervious to water the joints may be 25 composed of tar, asphalt, or other bituminous compound, thus adequately preventing infiltration of water or other liquid. Likewise, manholes and analogous vertically disposed tunnel-like structures may also be produced in accordance with the foregoing with a 100 per cent ceramic surface and without visible joints.

My invention therefore comprises a parallelepipedal block or brick having one side, one end and its bottom especially configured so as to provide new and useful features and results. Such 35 a brick not only makes it possible to more quickly and more simply produce built-up structures which are stronger and more durable as well as level but also the formation of certain types 40 of built-up structures wherein no spacers or pre-cast strips are required and wherein there are no visible or accessible joints, thus providing a structure extremely long in life and substantially entirely free from any ordinary form of deterioration, particularly as to the joints thereof. 45 The foregoing description and explanation are however intended as illustrative or exemplary rather than limitative and I may make certain additions, omissions, modifications or substitutions within the scope and principle of the foregoing. The invention is rather to be defined by 50 the appended claims, wherein the term brick is used in its broadest sense as covering bricks, blocks, tiles and similar articles forming units of building construction.

Having thus described my invention, what I claim as new and desire to secure by Letters Patent is:

1. A parallelepipedal brick having its bottom, 60 one end and one side surface provided with communicating recesses, the recesses in the side and end surfaces including an intermediate flute and the brick surface adjacent the flutes being disposed on a gradual inclination which slopes toward said flutes.

2. A parallelepipedal brick having its bottom, one end and one side surface recessed, the recesses in the end and side surfaces including an

intermediate flute connected by inclined surfaces which slope from the ends thereof toward the flute, each flute terminating in an enlarged semi-circular beveled recess formed partly in the 5 respective side and end surfaces and partly in the bottom surface and communicating with the recess in the bottom surface which is defined by a raised marginal projection along one side and spaced segmental projections along the other side. 10

3. A parallelepipedal brick the bottom surface of which is provided with a longitudinal marginal projecting portion along one edge and spaced, raised sectors along the other edge, there being a semi-circular beveled recess between said 15 spaced, raised sectors.

4. A parallelepipedal brick the bottom surface of which is provided with a longitudinal projection along one side and spaced, raised segmental projections along the opposite side, the bottom 20 surface aforesaid being provided with two beveled semi-circular recesses, one of which is located between the segmental projections and the other of which is located between one of the segmental projections and the end of the longitudinal projection. 25

5. A parallelepipedal brick, one side surface of which is provided with an inverted funnel-shaped recess and sloping side walls extending from a point near the ends of said side surface to said 30 recess, the extreme ends of said side surface being provided with marginal wedge-shaped projections which have a maximum height at the top of the brick and which merge into the side wall near the bottom of the brick. 35

6. A parallelepipedal ceramic brick, one side surface of which is provided with an inverted funnel-shaped recess, the side surface extending from such recess toward the ends thereof with a compound inclination, the termini of the side surface being constituted of vertical, marginal wedge-shaped portions tapering from top to bottom. 40

7. A parallelepipedal brick which has one end surface thereof provided with a centrally disposed flute, the bottom of the flute being connected to and merging with a substantially semi-circular beveled recess formed partly in the end surface of the brick and partly in the bottom surface thereof, the end wall being inclined toward the flute and being also inclined from bottom to top from the flute toward the outer corners of the brick, the extreme outer portions of the end wall surface being in the form of wedge-shaped projections which have their greatest thickness at the top of the brick and which merge into the wall surface adjacent the bottom thereof. 50 55

8. A parallelepipedal ceramic brick, one end surface of which is provided with an inverted funnel-shaped recess, the termini of the end surface being constituted of vertical, marginal wedge-shaped portions tapering from top to bottom, the end surface between the recess and the wedge-shaped portions being of compound inclination. 60 65
